UNITED STATES PATENT OFFICE.

WILLIAM DOUGLAS WEIR, OF CATHCART, GLASGOW, SCOTLAND, ASSIGNOR TO G. & J. WEIR, LIMITED, OF GLASGOW, SCOTLAND.

WITHDRAWAL OF AIR AND WATER OF CONDENSATION FROM STEAM CONDENSERS.

Application filed December 1, 1922. Serial No. 604,327.

To all whom it may concern:

Be it known that I, WILLIAM DOUGLAS WEIR, a subject of the King of Great Britain and Ireland, residing at Cathcart, 5 Glasgow, Scotland, have invented certain new and useful Improvements in the Withdrawal of Air and Water of Condensation from Steam Condensers; and I do hereby declare the following to be a full, clear, and 10 exact description of the invention, such as will enable others skilled in the art to which it appertains to make and use the same, reference being had to the accompanying drawings, and to letters or figures of reference marked thereon, which form a part 15 of this specification.

This invention relates to the withdrawal of air and water of condensation from steam condensers by the combined action of 20 a steam-jet air-ejector and a reciprocating air pump.

The invention will be described in the following specification and defined in the annexed claims. The characteristic features 25 of the invention are that the air pump is of the bucket type with admission valves, bucket valves, and discharge valves, that the ejector withdraws the air from the condenser and discharges it into the air pump 30 through a port which is situated above the admission valves and below the bucket when the latter is at the top of its stroke, and which is covered by the bucket during 35 a portion of its stroke, and that the air pump withdraws the water of condensation direct from the condenser, this water entering the pump through the admission valves.

It is to be understood that the words 40 "above" and "below" are employed for convenience and clearness of expression. They are used with the meaning which they have literally when the pump is vertical with the admission valves at the bottom and the discharge valves at the top.

The jet steam (of the ejector), together 45 with vapour withdrawn from the condenser with the air, may be condensed by contact with the water in the air pump barrel; or a 50 supplementary condenser may, for this purpose, be interposed between the ejector and the air pump.

When such a supplementary condenser is 55 employed, a second steam-jet ejector may be provided between this condenser and the air

pump, thus providing two-stage steam-jet air ejection.

The condensing water for the supplementary condenser (when such a condenser is employed) may be taken from the discharge of the air pump; and the supplementary condenser may be formed structurally in one with the air pump.

The invention is illustrated in the accompanying drawings which are diagrammatic.

Fig. 1 illustrates the carrying of the invention into effect in one convenient manner.

Fig. 2 illustrates the employment of two-stage steam-jet air ejection.

Figs. 3 and 4 illustrate the forming of the supplementary condenser in one with the air pump.

The same reference letters are used to 75 designate similar parts in the several figures.

Referring to Fig. 1, *a* is the main condenser and *b* is the air pump. The air pump is of the twin-barrel vertical type 80 with discharge at the top. It is provided with head or discharge valves, shown, in the case of one barrel at *c*, with bucket valves shown at *d* in the bucket *w*, and with foot or admission valves shown at *e*. The water 85 of condensation leaves the condenser by the pipe *f* which delivers it to the air pump below the foot valves.

The steam-jet air-ejector *g* withdraws the air from the main condenser by the pipe *h* 90 and delivers it into the supplementary condenser *k* where the steam of the jet, and the vapour drawn from the main condenser with the air, are condensed. The air and water of condensation are discharged from 95 the supplementary condenser by the pipe *p* and through non-return valves *v* (better seen in Figs. 2 and 3) into the two air pump barrels, entering the latter at *q*. The condensing water for the supplementary condenser is taken by the duct *m* from the discharge of the air pump.

The supplementary condenser may be omitted, and the steam from the ejector condensed in the barrels of the pump by 105 mingling there with the water of condensation.

When a supplementary condenser is employed, a second steam-jet air-ejector may be provided between this condenser and the 110

air pump, thus providing two-stage steam-jet air ejection, the steam from the second-stage ejector being condensed by mingling with the water of condensation in the pump. 5 Such an arrangement is shown in Fig. 2 where the second-stage ejector is indicated by the reference letter *n*. The first-stage ejector, supplementary condenser, and other elements or parts are represented by the 10 same reference letters as in Fig. 1.

When a supplementary condenser is provided and is supplied with condensing water from the discharge of the air pump, it may with advantage be formed structurally in 15 one with the air pump. Such an arrangement is shown in Figs. 3 and 4. Fig. 3 is a sectional elevation, and Fig. 4 a sectional plan.

The invention may be employed with air 20 pumps having a single barrel or with two, three, or more barrels, and driven direct by a steam cylinder or cylinders or in any other suitable manner.

Having thus described my invention, 25 what I claim as new and desire to secure by Letters Patent is:—

1. The combination with a steam condenser of a steam-jet air-ejector, a reciprocating air pump of the bucket type with 30 admission valves, bucket valves, and discharge valves, a port in said pump situated above the said admission valves and so situated that it is below the said bucket when the latter is at the top of its stroke and is 35 covered by the said bucket during a portion of its stroke, means whereby the air from the said condenser is withdrawn therefrom by the said ejector, means whereby this air is discharged into the said pump through 40 the said port, and a pipe connection whereby the said air pump withdraws the water of condensation direct from the condenser and delivers it into the said pump through the said admission valves.

45 2. The combination with a steam condenser of a steam-jet air-ejector, a reciprocating air pump of the bucket type with admission valves, bucket valves, and discharge valves, a port in said pump situated 50 above the said admission valves and so situated that it is below the said bucket when the latter is at the top of its stroke and is covered by the said bucket during a portion 55 of its stroke, a supplementary condenser, means whereby the air from the first mentioned condenser is withdrawn therefrom by the said ejector, means whereby this air is discharged through the said supplementary condenser and thereafter through the said 60 port into the said air pump, and a pipe

connection whereby the said air pump withdraws the water of condensation direct from the first mentioned condenser and delivers it into the said pump through the said admission valves. 65

3. The combination with a steam condenser of a steam-jet air-ejector, a reciprocating air pump of the bucket type with admission valves, bucket valves, and discharge valves, a port in said pump situated above the said admission valves, and so situated that it is below the said bucket when the latter is at the top of its stroke and is covered by the said bucket during a portion of its stroke, a supplementary condenser, a second steam-jet air-ejector, means whereby the said first mentioned ejector withdraws the air from the condenser and discharges it through the said supplementary condenser, means whereby the said second-mentioned ejector withdraws the air from the said supplementary condenser and discharges it through the said port into the said air pump, and a pipe connection whereby the said air pump withdraws the water of condensation direct from the first mentioned condenser and delivers it into the said pump through the said admission valves. 70 75 80

4. The combination with a steam condenser of a steam-jet air-ejector, a reciprocating air pump of the bucket type with admission valves, bucket valves, and discharge valves, a port in said pump situated above the said admission valves and so situated that it is below the said bucket when the latter is at the top of its stroke and is covered by the said bucket during a portion of its stroke, a supplementary condenser formed structurally in one with the said air pump, the water space in said supplementary condenser being connected up to the said pump in a manner to allow of water passing from the discharge of the said pump into the said supplementary condenser to act as condensing water therein, means whereby the air from the first mentioned condenser is withdrawn therefrom by the said ejector, means whereby this air is discharged through the said supplementary condenser and thereafter through the said 95 100 105 110 115 port into the said air pump, and a pipe connection whereby the said air pump withdraws the water of condensation direct from the first mentioned condenser and delivers it into the said pump through the said admission valves.

I hereby sign my name to this specification.

THE RIGHT HONOURABLE WILLIAM
DOUGLAS, BARON WEIR OF EASTWOOD P. C.
